UNITED STATES PATENT OFFICE.

JOHN E. GREENAWALT, OF DENVER, COLORADO.

APPARATUS FOR ROASTING OR SINTERING ORES.

1,348,407.

Specification of Letters Patent.

Patented Aug. 3, 1920.

Application filed November 18, 1910. Serial No. 592,997.

To all whom it may concern:

Be it known that I, JOHN E. GREENAWALT, a citizen of the United States, residing at Denver, in the county of Denver and State 5 of Colorado, have invented certain new and useful Improvements in Apparatus for Roasting or Sintering Ores; and I do declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

My invention relates to an improved apparatus for roasting ores and especially for desulfurizing and agglomerating or sintering the pulverized ore preparatory to smelting. The apparatus may also be employed 20 to treat ore with any suitable gas, as chlorin, for instance, where the object is to chloridize part or all of the metals contained in the charge. For example, this apparatus 25 is especially designed and constructed to utilize the down draft process of treating ore and other material set forth in Letters Patent No. 839,065, issued to me December 18, 1906.

30 The special object to be attained by my present invention in connection with the process protected by the aforesaid patent, is a simple and economical agglomeration of fine material and at the same time desulfurizing it sufficiently for smelting purposes. The operation is intermittent and based 35 upon the principle of passing the air or other gases downwardly through the ore mass and its porous support, as a grate, and thence through the exhauster or suction producing apparatus. When this use is made 40 of the apparatus the charge should contain sufficient combustible material to maintain the proper temperature to secure the results 45 desired. In sintering ores, for example, it is desirable to have at least 10% sulfur in the charge, which with the proper amount of air passing through the mass will produce sufficient heat to agglomerate the same.

50 In my experience, fifty cubic feet of air per minute for each square foot of grate area gives excellent results. The exhauster should be capable of giving at least 12 to 16 ounces of suction or vacuum pull. In 55 the operation of the plant, the charge properly moistened and thoroughly mixed, is

placed upon a porous layer or bed in a roasting pot or pan, this porous bed in turn being supported by a suitable grate or equivalent perforated member. By means 60 of a suction fan or other suitable exhauster, a current of air is passed downwardly through the charge, the bed, the grate and the exhauster. The upper surface of the charge is preferably ignited by a flame produced by atomizing oil. After the charge 65 has been ignited the oil is turned off and the combustion is supported by the combustible elements, such as sulfur and other impurities in the charge. In lieu of oil, I may employ 70 gasoline, powdered carbonaceous fuel, or any suitable gaseous fluid for the purpose of igniting the charge.

A complete plant for practising my invention may consist of a box-like cast iron 75 roasting pot or equivalent open top ore holder mounted on trunnions, one of which is hollow, through which the gases and combustion products are drawn into the exhausting apparatus. A portable igniter is 80 mounted so as to be removed from the pot during the operation of filling and discharging the latter. This igniter consists of a hood or cover shaped to harmonize with the top of the pot and fitting closely thereon when lowered into position. The igniter 85 may be suspended to travel over an area occupied by a series of pots, since one igniter may be employed in connection with a number of pots, the act of igniting the 90 charge of a single pot requiring only a very brief period, and as soon as this is done the igniter may be moved to the next pot, and so on down the line.

The igniting cover is equipped with spray 95 nozzles or ducts for atomizing the oil, and suitable openings are formed in the cover to allow the necessary air to enter for purposes of combustion. This oil is delivered to the atomizers under pressure, preferably 100 of about sixty (60) pounds per square inch. Hence, as soon as the oil is turned on, the chamber of the igniter above the charge is instantly filled with atomized oil sprayed into said chamber by the nozzles aforesaid. 105 In this form the oil is readily ignited, the burning particles filling the chamber with flame, and in about half a minute the entire surface of the charge is in an incandescent state, caused by the flame being brought 110 into intimate contact with the charge. The products of combustion escape through the

hollow trunnion of the pot. After the charge is sintered the pot is revolved on its trunnions and thrown to an inverted position, when the sintered mass or cake falls out and passes downwardly striking upon an inclined chute which is equipped with angle iron members adapted to break up the mass, which is rendered porous and brittle by the sintering operation. This angle iron chute serves to break up the ore to a considerable extent, but the larger pieces may be further broken by sledging or in any other suitable manner, so that the sintered product may pass through suitable openings at the bottom of the chute, through which it drops to receiving cars.

Having briefly outlined my improved construction, I will proceed to describe the same in detail, reference being made to the accompanying drawing in which is illustrated an embodiment thereof.

In this drawing:

Figure 1 is a vertical section taken through a plant equipped with my improved apparatus, one of the sintering pots being transversely sectionized.

Fig. 2 is a section taken on the line 2—2, Fig. 1, looking toward the left.

Fig. 3 is a side elevation of the apparatus showing a number of sintering pots arranged to be ignited by a single portable or traveling igniter.

The same reference characters indicate the same parts in all the views.

Let the numeral 5 designate a suitable upright framework upon which is supported, some distance from the bottom, a sintering pot 6 divided into upper and lower chambers or compartments 7 and 8 respectively by a grate or perforate member 9 carrying a porous layer 10 forming a pervious support upon which rests a charge 12 of pulverized ore to be sintered. This pot has a surrounding top rim or flange 13 upon which the lower flanged edge 14 of a cover or hood 15 is adapted to fit. This cover is formed hollow and of considerable depth whereby a mixing and ignition chamber 16 is formed, making it practicable to mingle the necessary fuel oil with air for purposes of combustion, the oil entering the mixing chamber of the igniter through spray nozzles or burners 17 and the air through narrow slots or openings 18 formed in the top of the cover. As illustrated in the drawing a number of nozzles 17 extend from transverse pipe sections 19 located at each end of the cover and are in communication with a central longitudinally disposed pipe 20 to which leads a flexible conduit 21 from an oil tank 22 in which the oil is maintained under pressure by air delivered into the top of the tank above the level 23 of the liquid through the agency of a pipe 24 connected with an air compressor

25. The conduit 21 contains a controlling valve 26 for shutting off and turning on the oil used in connection with the igniting mechanism. The nozzles 17 are first bent downwardly from the end pipes 19 and then 70 extend inwardly and slightly into the chamber 16 through openings 4 formed near the top of the sides of the cover, the nozzles on one side being disposed substantially diametrically opposite the corresponding nozzles on the opposite side.

The igniting cover 15 is equipped at each extremity with a bail 27. The upper extremity of each of these bails is pivotally connected, as shown at 28, with a hand lever 29 fulcrumed at 30 on a carriage 31 composed of end frames 32 connected by rods 33 and 34 and carrying wheels 35 engaging the base flanges 36 on opposite sides of an eye beam 37 secured to the top of the frame. 85 Each of these hand levers 29 is provided at its extremity opposite from the pivot 28 with a chain 38 whose links are adapted to engage a hook 39 formed on the top of the cover 15. It will thus be observed that the 90 cover may be raised and lowered by utilizing the chain extremities of these levers, the chains coöperating with the hooks to which they may be readily attached and from which they may be readily detached, 95 as circumstances may require.

Where the igniter is used in connection with a number of pots 6 as illustrated in Fig. 3, the flexible conduit 21 must be long enough to permit the necessary travel in 100 going from the pot at one extremity of the series to the other. In this event the oil tank 22 should, of course, be centrally located (see Fig. 3), and it may be assumed that the line of pots 6 in this view is extended in both directions until say ten or a dozen pots are arranged in a line, the charges of all of which may be ignited by the use of a single portable igniting apparatus of the character illustrated and described herein.

Each pot 6 is trunnioned at its extremities as shown at 40 and 41. The trunnion 41 is hollow and a tight joint is formed around the same by the employment of a sort of 115 stuffing box 42. The opening 43 through this trunnion communicates with the air and gas compartment or chamber 8 of the pot below the grate and also with a chamber 44 enclosed by a housing 45 from which a duct or down conduit 46 leads to an exhauster 47 operated from a motor 48 through the agency of a belt 49. A belt 50 also leads from the motor to the air compressor 25 (see Fig. 1). When the igniter is used in connection with 125 any pot, the chamber 7 of the latter having been first charged with ore, the cover 15 is dropped down to engagement with the rim of the pot with which it forms a seal or air-and-gas tight joint. The oil is then 130

turned on by opening the valve 26, causing the oil by virtue of the pressure from the tank 22 to be forced through the nozzles 17 and thence into the chamber 16 of the igniting cover, with sufficient force for atomizing purposes. The atomized oil is then ignited, filling the ignition chamber 16 with flame, and the suction apparatus or exhauster being in operation, the flames and hot combustion products from the burning oil are drawn downwardly through the open bottom of the chamber into the previous layer or charge of ore, the operation being continued until the combustible material, principally sulfur, of the ore is thoroughly ignited. The oil is then turned off by the closing of the valve 26, and, if desired, the cover may be lifted sufficiently to clear the pot, after which the cover is moved along upon its carriage out of the way or to the next pot, where a series of pots is employed, the same operation being repeated with each pot. The ore charge having been ignited by the temporary application thereto of the flames and combustion products as above described, the combustible material in the ore will thereafter maintain the combustion, furnishing the necessary fuel until the sintering operation is complete. The charge having been sintered, and the igniting cover 15 moved out of the way, the pot 6 is then turned on its trunnions by pushing downwardly on one side or the other until its position is reversed, its top being down as indicated by dotted lines in Fig. 1. The charge will then fall out and pass downwardly striking upon an inclined chute 51 where it engages the upwardly projecting flanges 52 of a series of angle irons 53 which breaks it up to a considerable extent. The ore then moves downwardly on the chute to openings 54 formed at the lower extremity thereof through which it passes. If any chunks or pieces are too large to pass through these openings into the cars 55 below, they may be further broken by sledging as heretofore stated.

An important object subserved by the cover or hood 15 is that when deposited over the pot or receptacle 6, and the fuel is turned on, the igniting flames in response to the suction of the exhauster, are drawn against the surface of the charge of ore, and the entire surface of such charge is simultaneously ignited. This simultaneous ignition of the entire ore-charge surface is one of the indispensable features of the present invention, enabling as it does the zone of combustion to progress evenly through the entire ore charge without danger of becoming localized or having its action confined to restricted areas. In practice the dimensions of the pot 6 are approximately six by eight feet and in some instances the size of the pot is even greater. It is indispensable therefore, with a pot having so extended an area, that the entire

surface of its charge shall undergo simultaneous, thorough and complete ignition so that a corresponding roasting or sintering action may follow.

Having now described my invention, what I claim is:

1. In combination with an open top holder for a charge of material to be treated, an igniting member movable relatively to said holder and adapted to be temporarily positioned over the holder and its charge in non-movable relation thereto, and operating to ignite the charge at its surface while so positioned. 75

2. In combination with an open top holder for a charge of material to be treated, a flame-confining hood adapted to be superposed over the holder and its charge for igniting the charge at its surface. 80

3. In combination with an open top holder for a charge of material to be treated, an igniting cover or hood adapted to be positioned over the holder and its charge and operating to ignite the charge at its surface when so positioned. 85

4. In combination with an open top holder for a charge of material to be treated, an igniting cover or hood adapted to be temporarily positioned over the holder and its charge and operating to ignite the charge at its surface while so positioned. 90

5. In combination with an open top holder for a charge of material to be treated, a flame-confining igniting cover or hood adapted to be positioned over the holder and its charge and operating to ignite the charge at its surface when so positioned. 100

6. In combination with an open top holder for a charge of material to be treated, a flame-confining igniting cover or hood adapted to be temporarily positioned over the holder and its charge and operating to ignite the charge at its surface while so positioned. 105

7. In combination with an open top holder for a charge of material to be treated, a portable igniting cover or hood adapted to be positioned over the charge and operating to ignite the charge at its surface when so positioned. 110

8. In combination with an open top holder for a charge of material to be treated, a portable igniting cover or hood adapted to be positioned over the charge and form above the charge a suitable ignition chamber, and means for delivering to said chamber fuel in suitable form for igniting the charge at its surface. 115

9. In combination with a pan adapted to receive a charge of material to be treated, a portable hood adapted to be applied to the top of the pan, and equipped with means for feeding fuel in fluent form above the charge for igniting the charge at its surface. 125

130

10. In combination with a plurality of separated pans arranged in suitable proximity to one another and respectively adapted to receive charges of material to be treated, 5 a portable igniter comprising a cover for closing the top of any pan and form an ignition chamber above the charge in said pan, and provided with means for feeding fuel in fluent form into said chamber, the 10 igniter being supported to travel from pan to pan for successively igniting the charges of the several pans.
11. An apparatus for agglomerating or sintering ore, comprising a pervious support for a thin bed of ore, a chamber surmounting the support and its charge, means for causing a supporter of combustion to pass into said chamber, thence through the ore and its support throughout the entire 15 20 25 30 35 40 45 50 55 60 65 70 75 80 85 90 95 100 105 110 115 120 125 130 agglomerating or sintering operation, and means for igniting the material at its surface by causing flaming particles and highly heated products of combustion to be temporarily passed into said chamber.
12. An apparatus for agglomerating or sintering ore, comprising a pervious support for a thin bed of ore, a chamber having perforate walls surmounting the support and its charge, means for causing a supporter of combustion to pass into said chamber through the walls thereof, thence through the ore and its support throughout the entire agglomerating or sintering operation, and means for igniting the material by causing flaming particles and highly heated products of combustion to be temporarily maintained in said chamber in contact with the surface of the supported bed of ore.
13. In an apparatus for agglomerating or sintering ore, the combination of a perforated support for a pervious bed of ore, means for causing a supporter of combustion to pass through the ore bed and its support throughout the entire agglomerating or sintering operation, and an igniter covering but spaced from the charge, provided with a fluid hydrocarbon burner arranged to temporarily project a broad and intense mass of flaming particles into the space above the surface of the ore, which are drawn into intimate contact with the area of said surface by the supporter of combustion caused to pass through the ore bed.
14. In an apparatus for agglomerating or sintering ore, the combination of a perforated support for a pervious bed of ore, means for causing a supporter of combustion to pass through the ore bed and its support throughout the entire agglomerating or sintering operation, and an igniter having perforated walls covering but spaced from the charge, provided with a fluid hydrocarbon burner arranged to temporarily project a broad and intense mass of flaming particles into the space above the surface of the ore.
- ore, which are drawn into intimate contact with the area of said surface by the supporter of combustion caused to pass through the ore bed.
15. In an apparatus for agglomerating or sintering ore, the combination of a perforate support for a thin bed of ore, means for causing a supporter of combustion to pass through the ore throughout the entire agglomerating or sintering operation, an ignition chamber above the charge, and a pair of spray burners carried by the walls of the said chamber at points substantially diametrically opposite each other near the opposite edges of the supported bed of ore.
16. In an apparatus for agglomerating or sintering ore, the combination of a perforate support for a thin bed of ore, means for causing a supporter of combustion to pass through the ore throughout the entire agglomerating or sintering operation, an igniter having perforate walls covering but spaced from the charge and forming a mixing chamber above the charge, and spray burners on the igniter for temporarily projecting into said mixing chamber a broad and intense mass of flaming particles for igniting the ore at its surface.
17. In an apparatus for agglomerating or sintering ore, a perforate support for a thin bed of ore, an igniting hood for covering and setting fire to the ore while upon the support, and means for causing currents of air or other supporter of combustion to pass through the ore while covered by the hood.
18. In an apparatus for agglomerating or sintering ore, a perforate support for a thin bed of ore, an igniting hood having perforate walls for covering and setting fire to the ore while upon the support, and means for causing currents of air or other supporter of combustion to pass through the perforations in the walls of the hood and through the ore while covered by the hood.
19. In an apparatus for agglomerating or sintering ore, a perforate support for a thin bed of ore, an igniting hood for covering and setting fire to the ore while upon the support, said hood having perforate walls spaced from the surface of the ore charge, an air compartment arranged below said support, and means for causing a supporter of combustion to enter the hood through the perforated walls thereof and pass thence through the ore and into the compartment below the ore support, and then out of said compartment.
20. In an apparatus for agglomerating or sintering ore, the combination of a perforate support for a thin bed of ore, an igniting hood for covering and setting fire to the ore while upon the support, said hood being provided with a mixing chamber, means for feeding into said chamber suitable ignition

- fuel, means for causing a supporter of combustion to enter the mixing chamber to maintain combustion therein, and means for causing the gases to pass through the ore and through the perforate support. 5
21. In an apparatus for agglomerating or sintering ore, the combination of a perforate support for the ore, a flame-confining igniting hood for covering the ore while upon the support and directing the hot products of combustion into intimate contact with the surface of the ore to be ignited, and means for causing currents of a gaseous supporter of combustion to pass through the ore while 10 covered by the hood. 15
22. In an apparatus for agglomerating or sintering ore, a perforate support for a thin bed of ore, an igniting flame-confining hood for covering the ore and setting fire to the ore at its surface while upon the support, means for cutting off the igniting flame, and means for causing combustion of the ore to be continued after the igniting flame has 20 been cut off. 25
23. In an apparatus for agglomerating or sintering ore, a perforate support for the ore, and an igniting hood for covering, and setting fire to the ore at its surface while upon the support. 30
24. In an apparatus for agglomerating or sintering ore, a suitable holder, a perforate support for the ore in said holder, and an igniting hood for covering and setting fire to the ore at its surface while upon the support, the hood forming with the surface of the ore charge a suitable mixing chamber, and means for admitting air or other supporter of combustion to said mixing chamber. 35
25. In an apparatus for agglomerating or sintering ore, a pervious support for the ore, and a flame-confining igniting hood for covering, and setting fire to the ore at its surface while upon the support. 40
26. In an apparatus for sintering ore, the combination with means for holding a body of ore disposed in a layer, of an igniting hood or cover for the ore having a chamber with an open bottom and arranged to 45 confine hot igniting materials and direct the heat therefrom to an area of the ore mass corresponding with the area of the open bottom of the chamber. 50
27. In an apparatus for agglomerating and sintering ore, a support for a pervious bed of ore, means for causing a supporter of combustion to pass through the ore, and an igniting hood or cover provided with a chamber in which is temporarily maintained 55 a supply of products of combustion heated to an ore-igniting temperature and directed against the surface of the ore exposed to said chamber. 60
28. In an apparatus for forming cakes of agglomerated or sintered ore from a mass 65 initially containing a metal-bearing material in pulverized form and also a combustible ingredient, the combination of a holder adapted to have disposed therein a relatively thin layer of said mass and having a perforate support on which the mass rests, the walls of the holder surrounding the said mass, an igniting cover movable relatively to the holder for setting fire to the ore at its surface, and means for causing combustion-supporting gas to pass through the said layer, the holder being tilttable to permit discharge of the sinter upon removal of the igniting cover. 70
29. In an apparatus for forming cakes of agglomerated or sintered ore from a mass initially containing a metal-bearing material in pulverized form and also a combustible ingredient, the combination of a tilttable holder adapted to have disposed therein a relatively thin layer of the mass, and having a perforated support for the ore, the walls of the holder surrounding said mass, a relatively movable igniting cover having perforate walls adapted to be positioned over the ore mass and form a mixing chamber above the surface of the ore, and means for causing combustion-supporting gas to pass through the walls of the cover, into the mixing chamber and through the said layer and 80 its support, the finished sinter being free to discharge upon a removal of the cover and tilting of the holder. 85
30. In an apparatus of the class described, the combination of a pan adapted to receive a charge of ore or other material to be treated, a portable hood adapted to fit the top of the pan and equipped with nozzles at each end thereof for delivering fuel in fluid form to the charge, the bottom of the pan 90 having openings, and means connected with the bottom of the pan for exhausting the products of combustion by drawing them down through the charge and out through the bottom of the pan, for the purpose set forth. 95
31. The combination of a pan whose bottom forms a support for the charge to be treated, an igniter comprising a hollow cover adapted to fit the top of the pan and forming a chamber above the same for mixing air with fuel in fluid form, the cover being equipped with nozzles located at each end thereof for feeding the fuel to the mixing chamber, and means for exhausting the 105 products of combustion by drawing them down through the charge, the support for the material having openings therein, for the purpose set forth. 110
32. The combination with a number of separated pans, arranged in suitable proximity to each other and adapted to respectively receive the charges of material to be treated, and a portable igniter consisting of a hollow cover adapted to close the top of 120 125 130

each pan and equipped with means for feeding fuel to the charge in fluid form, the igniter being supported to travel from one pan to another, for successively igniting the 5 charges of the several pans.

33. In combination with a receptacle having a support for the charge, said support having openings for the traverse of gases from the charge, an exhauster, means responsive to the action of the exhauster for effecting a simultaneous ignition of the charge throughout the entire surface thereof, and means for excluding cross air currents from the charge thereby producing a zone 10 of combustion progressing uniformly throughout, and coextensive with, the charge.

34. The combination of a number of pans arranged in suitable proximity to each other 20 and adapted to respectively receive charges of material to be treated, and a portable igniter consisting of a hollow cover adapted to close the top of each pan and equipped with means for feeding fuel to the charge in fluid form, the igniter being supported by means of an overhead carriage to travel from one pan to the other for successively igniting the charges of the several pans, substantially as described.

30 35. In combination with a receptacle having a support for the charge, said support having passages for the traverse of gases from the charge, and an igniting hood coextensive with the area of the charge positioned over the receptacle and making a seal with the walls thereof against influx of cross atmospheric currents into the bottom of the hood, whereby a zone of combustion uniformly and simultaneously permeating the 35 entire charge, is maintained.

36. The combination of a pan adapted to receive a charge of material to be treated, the pan being trunnioned for dumping purposes, and a portable igniter adapted to be 45 applied to the top of the pan and equipped with means comprising nozzles located at each end thereof, for feeding fuel thereto in fluid form, the igniter being movable away from the pan to allow the latter to turn 50 on its trunnions for dumping purposes, substantially as described.

37. The combination of a pan provided with a support for the charge to be treated, the support having an opening therein, 55 means for exhausting the products of combustion by drawing them down through the charge and through the support, and a cover adapted to close the top of the pan and equipped with nozzles located at each end thereof for feeding fluid fuel under pressure thereto, substantially as described.

38. In an apparatus of the class described, the combination of a pan adapted to receive a charge of ore or other material to be 65 treated, the pan being equipped with a sup-

port for the charge, the support having an opening therein, a portable hood adapted to fit the top of the pan and equipped with nozzles at each end thereof for delivering fuel in fluid form and under pressure to the 70 charge, and means connected with the pan for exhausting the products of combustion by drawing them down through the charge and its support, for the purpose set forth.

39. A sintering apparatus, comprising a 75 receptacle rotatable about a fixed axis and having an upper compartment for the charge and a compartment below the charge communicating with the upper compartment through the charge and its support, a hollow 80 trunnion leading from the lower compartment and disposed about the rotation axis of the receptacle, an exhauster coupled to the trunnion, a hood or cover adapted to be temporarily placed over the charge, and means on said hood for supplying an inflammable mixture adapted to be drawn 85 toward the surface of the charge whereby the entire area of said surface may be simultaneously ignited.

40. A sintering apparatus comprising a receptacle having a perforated member for the support of the charge, an exhauster for drafting gases downward through the charge and through said perforated member, a hood adapted to be temporarily positioned over the receptacle and charge, and means on said hood for delivering fuel and air over the charge whereby the ignition gases are drafted over the surface of the charge and the 100 latter is ignited simultaneously substantially throughout its entire area, the hood making an air-tight joint with the walls of the receptacle whereby cross air currents are excluded and the zone of combustion is 105 caused to permeate the entire charge.

41. A sintering apparatus comprising a receptacle having a perforated support for the charge, an exhauster for drafting gases downward through said charge and through said support, a hood adapted to be temporarily positioned over the receptacle and form a combustion chamber above the charge, sealed at the bottom against access of atmospheric cross currents, and means for filling said chamber with inflammable material whereby the entire surface of the charge is simultaneously ignited and the gases drawn through the entire charge, and whereby the zone of combustion uniformly permeates the 115 entire charge.

42. A sintering apparatus comprising a tilting receptacle having a perforated support for the charge, an exhauster for drafting gases downward through the charge and its support, a removable hood temporarily deposited on the receptacle and forming a combustion chamber above the charge sealed at the bottom against access of atmospheric cross-currents, and means carried by the 125 130

hood for filling said chamber with igniting gases whereby the entire surface of the charge is simultaneously ignited and the roaster gases are drawn evenly through the charge toward the exhauster, the seal aforesaid preserving the integrity of the zone of combustion throughout the entire charge.

43. In an apparatus for agglomerating or sintering ore, a perforate support for a thin bed of ore, a hood for covering practically air-tight the ore while upon the support, means for causing a supporter of combustion to pass downwardly through the ore while covered by the hood, and an igniter 10 located within the hood for setting fire to the ore at its surface.

44. In an apparatus for forming relatively thin cakes of agglomerated or sintered ore from a mass initially containing a metal-bearing material in pulverized form and a combustible ingredient, the combination of an open-top holder adapted to have disposed therein a relatively thin layer of the said mass and having walls surrounding the 20 said layer and a perforate bottom on which it rests, an air-supplying mechanism, a hood having an open bottom adapted to be temporarily in air-tight connection with the said open top of the said holder, igniting 25 means within the hood arranged to set fire to the combustible ingredients at the surface of the said mass, and means for tilting the holder to remove the sinter cake formed therein from the walls which surround it.

45. In an apparatus for forming relatively thin cakes of agglomerated or sintered ore from a mass initially containing a metal-bearing material in pulverized form and also a combustible ingredient, the combination of 30 a box-like holder for a relatively thin layer of the said mass having a perforated bottom, arranged between an upper ore chamber and a lower gas chamber thereof, a super-jacent air-hood with which the said ore 35 holder can have temporary gas-tight connection, the hood and holder being separable, means in the hood for causing ignition of the combustible element of the mass at the upper surface of the layer thereof, means 40 for causing combustion-supporting gas to move downwardly through the hood, through the region of ignition, and then through the ore layer, and a duct below the ore holder adapted to communicate with the 45 gas chamber thereof for carrying away the air and gases which pass through the ore mass in the holder.

46. In an apparatus for forming relatively thin cakes of agglomerated or sintered ore 50 from a mass initially containing a metal-bearing material in pulverized form and also a combustible ingredient, the combination of

a box-like holder for a relatively thin layer of the said mass having a perforated bottom, arranged between an upper ore chamber and a lower gas chamber thereof, a super-jacent hood with which the said ore-holder can have temporary gas-tight connection, the hood and holder being separable, means in the hood for causing ignition of the combustible element of the mass at the upper surface of the layer thereof, means for causing combustion-supporting gas to move downwardly through the hood, through the region of ignition, and then through the ore 65 layer, a duct below the ore-holder adapted to communicate with the gas chamber thereof for carrying away the air and gases which pass through the ore mass in the holder, and means for tilting the holder to discharge the 70 sintered ore therefrom.

47. An igniter for use in ore sintering apparatus comprising an open-bottom chamber located above a layer of ore the surface of which is to be ignited, and adapted to 85 be filled with particles heated to an ore-igniting temperature, the said chamber having closed sides arranged to confine and direct the hot materials therein.

48. In an apparatus for sintering ore, the 90 combination of a holder having a pervious grate adapted to support a thin pervious layer of ore, an igniter comprising a chamber arranged above the surface of the ore, and adapted to contain, confine and direct 95 downwardly, hot ore-igniting materials, a duct leading to the chamber through which may be supplied a gaseous fluid for maintaining the supply of hot materials within the chamber, and means for causing air to 100 be drawn down through the ore and its bed, whereby the heated contents of the said chamber are drawn therefrom into the body of ore.

49. In a sintering apparatus, the combination of a support for a body of ore having a pervious grate on which the ore is disposed in a thin pervious layer, an igniter for the ore comprising a chamber closed at its sides for confining hot materials for igniting the 105 ore, and means for drawing air through the body of ore to induce and maintain internal combustion in the mass thereof, the said chamber of the igniter being open to admit air thereto, whereby the gaseous contents 110 thereof are brought into contact with the ore to insure uniform igniting at the surface thereof.

In testimony whereof I affix my signature in presence of two witnesses.

JOHN E. GREENAWALT.
